UNITED STATES PATENT OFFICE.

JOHN R. HAMILTON, OF YONKERS, NEW YORK, ASSIGNOR TO SYPHO-CHEMICAL SPRINKLER CORPORATION, OF CROTON-ON-HUDSON, NEW YORK, A CORPORATION OF NEW YORK.

CHEMICAL FIRE-EXTINGUISHING APPARATUS.

1,264,393.

Specification of Letters Patent. Patented Apr. 30, 1918.

Application filed August 4, 1915. Serial No. 43,536.

To all whom it may concern:

Be it known that I, JOHN R. HAMILTON, of Yonkers, county of Westchester, State of New York, have made certain new and useful Inventions Relating to Chemical Fire-Extinguishing Apparatus, of which the following is a specification, taken in connection with the accompanying drawings, which form part of the same.

10 This invention relates especially to fire extinguishing apparatus in which the distributing system may comprise automatic or other distributing devices and in which a chemical mixing tank may be used to supply supplemental extinguishing liquid to the system. The mixing devices coöperating with the tank may comprise a primary or starting chemical chamber having a discharge connection through which the chemical tends to discharge, but which may be provided with a trapped or other retaining portion in which a mercury or other liquid seal restraining device may be normally held until it is withdrawn on the emergency operation of the system, thus releasing the primary charge of acid or other chemical which is discharged into the tank to generate the high emergency pressure therein. Supplemental pressure maintaining devices 25 may be used to preferably maintain the emergency discharge pressure substantially constant and these devices may comprise a supplemental chemical feeding chamber and connected pressure governing chamber above between which a charge of mercury may be transferred by the tank pressure to act as an automatic plunger and feed additional acid into the tank whenever the tank pressure decreases below the predetermined amount.

In the accompanying drawings showing in a somewhat diagrammatic way illustrative embodiments of this invention—

Figure 1 is a vertical section showing one form of apparatus.

Fig. 2 shows a modified construction.

Fig. 3 shows another embodiment.

Fig. 4 is a detail section thereof showing the parts in another position; and

50 Fig. 5 shows still another embodiment of the invention.

In the illustrative embodiment of the invention shown in Fig. 1 the distributing system, which may be of any desired form

and arrangement, may comprise a supply pipe, such as 8, with which are connected one or more distributing lines 6 having any suitable distributing devices, such as the automatic sprinkler heads 7, arranged at suitable points throughout the building. The distributing system is preferably normally charged with suitable extinguishing liquid, such, for example, as a suitable non-freezing solution which is normally kept at sufficient pressure to discharge from the distributing devices by a suitable priming actuating tank, such as 32, extending upward, so that the non-freezing or other extinguishing liquid 33 has sufficient head to discharge from the operating emergency devices. In case non-freezing solution is used in the system a check valve, such as 4, is preferably arranged at the lower portion of the supply pipe which may be connected with a supplemental supply of extinguishing liquid which may, if desired, comprise a chemical pressure tank such as the chemical mixing tank 1 into which extends the supply connection 2 communicating with the supply pipe 3. If desired, a suitable venting device such as the automatically closing ball check 5, may be arranged below the check valve 4 in which case it is sometimes desirable to have an equalizing opening, such as the pin hole vent 60 between the supply connection and the upper part of the mixing tank which may, if desired, be filled with an extinguishing liquid having in solution a pressure-generating chemical, such, for instance as the ordinary carbonate extinguishing liquid 8.

Any suitable chemical mixing devices may be arranged in coöperation with the mixing tank and may comprise a starting device adapted under fire emergency conditions to discharge into the tank a sufficient quantity of chemical to generate in connection with the chemical charge already in the tank the desired emergency discharge pressure of 50 to 100 pounds or so per square inch with which the extinguishing liquid is discharged from the operating distributing devices. This starting device may, for example, comprise a primary or starting chemical chamber 17 containing a charge 18 of suitable pressure generating chemical or solution located within the casing 14 connected to the tank and having

a removable cover 15, if desired. This starting charge normally tends to discharge into the mixing tank through a discharge connection which may comprise the trap 27 and the discharge pipe 30 extending through the open throat 31 of the casing, a suitable equalizing opening 19 being arranged in the top of the chamber to facilitate this discharge. A suitable restraining device 10 may coöperate with the discharge connection so as to normally restrain the discharge of the starting chemical therethrough and for this purpose it is desirable to employ a liquid seal or plug 28 of such character and composition as not to be undesirably acted on by the starting chemical and to effectively restrain its discharge, mercury being a convenient and effective liquid seal for this purpose when the starting charge is of sulfuric acid, for instance. This restraining mercury seal or plug may be normally held in the position indicated in Fig. 1 by the fluid pressure in the system as by allowing this pressure to be exerted 20 through the actuating pressure pipe 9 on the actuating chamber 10 which contains a charge 11 of mercury so that under these conditions the normal pressure in the system forces part of this mercury up through 25 the actuating transfer pipe 13, the lower part 12 of which extends adjacent the bottom of the chamber so as to maintain an effective restraining liquid seal or plug 28 in the discharge connection which is forced 30 upward in the trap sufficiently to sustain the pressure caused by the starting charge 18 above. Under emergency conditions when one or more of the distributing devices opens and liquid from the system is 35 discharged therethrough the pressure exerted in the actuating chamber is correspondingly decreased and the mercury from the transfer pipe and trap reënters the actuating chamber so as to allow a free passage 40 through the trapped discharge connection through which the acid or other chemical charge 18 quickly flows into the mixing tank, a venting passage 26 being arranged 45 in the upper part of this discharge connection in case it is desired to prevent siphon action, although otherwise this passage is unnecessary. This rapidly generates the 50 emergency chemical gas pressure within the tank and forces the extinguishing liquid up through the supply connection so as to close 55 the venting device 5 and open the check valve 4 so as to supply liquid to the distributing system for high pressure discharge from the operating distributing devices. Under these conditions the pressure 60 of the gas in the upper part of the mixing tank and connected casing equals or exceeds the pressure in the supply pipe 3 so that the mercury remains within the actuating 65 chamber and has no tendency whatever to

interfere with the flow of any remaining part of the starting charge 18 into the tank. Any suitable means may be employed to maintain the desired high emergency pressure in the mixing tank while the charge of extinguishing liquid is being discharged from the system and preferably suitable chemical mixing devices are arranged in connection with the tank to maintain this emergency discharge pressure substantially constant 70 throughout at least the greater part of the discharge from the tank. Fig. 1 illustrates one of a number of suitable supplemental chemical mixing devices which may be used for this purpose in connection with the starting devices shown in this form of the invention and as therein indicated a supplemental chemical or acid holder 21 may be arranged or formed as one chamber of the multiple receiver 16 within the casing 14 and 75 preferably provided with the upper vent or opening 20 so as to normally contain a suitable supplemental charge 22 of pressure generating chemical or acid adapted to react with the chemical 8 in the mixing tank 80 below. Under emergency conditions this supplemental chemical charge is adapted to be transferred to the supplemental chemical or acid feeding chamber 23 as by passing 85 through the holder discharge passage or pipe 25 which may be normally closed by any convenient device, such for instance as the seal or plug 24 of suitable liquid, such for example, as mercury, which may partly fill the feeding chamber under normal conditions. Under emergency conditions when 90 the high emergency pressure is chemically generated in the tank this mercury seal 24 may be largely or partly forced out of the feeding chamber as through a transfer pipe 95 25 so that the lower end of the holder discharge pipe 25 is thus uncovered and the supplemental charge of chemical or acid 100 22 thereupon bodily descends into the supplemental feeding chamber 23 which is of such size as to be thus substantially filled 105 with this supplemental chemical charge which is subsequently gradually fed into the mixing tank whenever the emergency pressure falls so that through suitable coöperating governing means or devices the emergency discharge pressure may be maintained 110 substantially constant in the mixing tank and connected distributing system. These governing devices may comprise a pressure 115 governing chamber, such as 36, arranged at such height above the feeding chamber as to produce a gravity pressure head of the mercury or other liquid seal substantially equal to the emergency discharge pressure in the 120 tank. This pressure governing chamber is preferably made of such capacity so that together with the governing transfer pipe 25 connecting it with the control chamber the mercury charge in these parts substantially 125 130

fills this governing chamber when the mercury is forced up into it to such extent as to first uncover the lower end of the holder discharge pipe. Any suitable over-pressure control devices may be arranged in connection with the pressure governing chamber so as preferably to considerably increase the pressure or liquid resistance exerted against any further passage of the mercury from the feeding chamber into the governing chamber and this may be conveniently effected by having a relatively small area over-pressure reservoir pipe 38 connected to the pressure-governing chamber so that the entrance of any further mercury into this governing chamber forces mercury into this over-pressure reservoir pipe and causes such a rapid rise therein as to produce a correspondingly rapid increase in the gravity head thus exerted and correspondingly minimize the danger of the mercury seal pressure device being rendered ineffective. Under emergency conditions after the mercury has been forced up to substantially fill the pressure-governing chamber 36 and after the acid 22 has descended into the supplemental feeding chamber to substantially fill the same above the thin layer of mercury remaining in the bottom of this chamber any decrease in the gas pressure within the mixing tank causes a corresponding descent of the mercury from the governing chamber into the supplemental feeding chamber 24 so as to force a corresponding amount of the acid over the discharge lip 34 of this feeding chamber down into the acid discharge pipe 30 communicating with the mixing tank. This quickly generates additional pressure in the tank and tends to force the mercury back from the feeding chamber into the pressure governing chamber. The chemical or acid is thus gradually fed from the feeding chamber in a series of relatively small increments whenever the emergency pressure begins to fall in the tank and by making the supplemental feeding chamber and the pressure governing chamber of such proportions as to be relatively flat or shallow the emergency pressure within the mixing tank may be regulated quite closely. By arranging the pressure governing chamber several feet above the supplemental feeding chamber so as to secure a mercury pressure head of 50 to 100 pounds or so per square inch which is sustained under emergency conditions by the gas pressure within the mixing tank any decrease in this gas pressure of a few pounds such as would allow the level of the mercury in the pressure governing chamber to fall from the top of that chamber to about the point indicated by the dotted line 37 would cause a corresponding volume of mercury to flow from the governing chamber into the feeding chamber where it would act as a feeding plunger or piston to feed a corresponding volume of acid or pressure generating chemical into the mixing tank. Under some conditions it is desirable to limit the rate at which acid is discharged from the supplemental feeding chamber so as to prevent an undesirable sudden rise of pressure in the tank and for this purpose the effective area of the governing transfer pipe 35 may be properly proportioned or controlled preferably by interposing therein a throttling check valve, such as 75, which is adapted to be held down on its seat 76 when the mercury descends during one of these feeding impulses, so that all the mercury is then forced to pass through the restricted throttling passage 79 in this valve. The valve is, however, allowed to rise against the action of the light spring 78 shown above it so that the valve engages suitable stops or guides 77 so as to allow the free upward passage of the mercury during the start of the emergency operation of the device, for instance, the size of these parts being somewhat exaggerated in Fig. 1 for greater clearness.

A somewhat similar starting device is shown in Fig. 2 as comprising the starting chamber 17 containing the charge 18 of starting chemical or acid which tends to discharge into the mixing tank 1 through the discharge connection 67 preferably comprising the trap 68. A restraining device automatically actuated on the emergency condition of the distributing system is arranged to coöperate with this discharge connection and may comprise the liquid or mercury seal 100 normally forced up the transfer pipe 13 from the actuating chamber 10 by the pressure exerted on the upper surface of the mercury 11 in this actuating chamber by a suitable actuating connection or pipe 80 which may normally communicate with the priming actuating tank 32 or other upper part of the distributing system so as to receive liquid 33 therefrom. As indicated in Fig. 2 this charge of extinguishing liquid in the distributing system may in some cases be the same as the chemical charge 8 in the mixing tank and this arrangement may be effected by keeping normally a sufficient air pressure in the mixing tank 1 so as to force the extinguishing liquid up to the top of the system where a sight glass 81 indicates its normal position. Under fire emergency conditions when one of the distributing devices comes into operation the liquid is discharged from the system and sufficient suction or pressure reduction is thus developed in the substantially closed upper part of the distributing system with which the suction actuating pipe 80 communicates, so that a suction impulse of a number of pounds or so is thus exerted on the actuating chamber 10 and the mercury seal 28 is thus quickly withdrawn from the trap 68 and the starting charge 18 thus quickly flows over the lip 69

and through the discharge pipe 67 without the necessary action of any solid moving parts. The chemical pressure then developed in the tank causes a flow of liquid 5 through the supply pipe 3, the inertia and friction effects of the liquid in these pipes being sufficient to make the air pressure in the tank exceed for a time at least after the distributing devices begin to operate, the pressure 10 initially caused by the actuating pipe 80 in the actuating chamber 10 so that by making the area of the discharge pipe 67 ample the certain discharge of all of the starting charge 18 may be effected. By arranging 15 the lower end 81 of the suction actuating pipe 80 in such position that it dips into the mercury 11 in the tank before the relatively large area transfer pipe 13 is free from mercury, an effective mercury seal is 20 always maintained between the gas space of the mixing tank and the upper part of the system.

By thus quickly discharging a predetermined amount of acid or pressure generating chemical 18 into the mixing tank the desired emergency pressure can be developed therein and this pressure can thereafter be maintained substantially constant by any suitable pressure maintaining devices of a chemical 25 mixing character, for instance, the supplemental chemical or acid chamber 70 may for this purpose be arranged within the casing 14 and may be partly filled with a supplemental charge 71 of acid or other pressure 30 producing chemical which is gradually discharged through a siphon discharge pipe 72, the lower end 73 of which is adjacent the bottom of the supplemental chamber, whenever the emergency gas pressure in the tank falls. 35 When the system comes into emergency operation the air and gas in the tank pass into this discharge spout 72 so as to develop the same emergency pressure within this supplemental chamber and then when the pressure 40 in the tank falls a few pounds this pressure within the chamber is sufficient to force out an increment of the acid or chemical charge which passes out of the spout 72 into the discharge pipe 74 communicating with 45 the tank. Thus additional gas pressure is chemically created and a substantially constant emergency pressure can be maintained throughout a large part at least of the discharge of the extinguishing liquid from the 50 tank.

Another suitable arrangement is indicated in Fig. 3 as preferably though not necessarily comprising a wet pipe distributing system which may be charged with non-freezing extinguishing liquid 33 separated by the check valve 4 from the supply connection 53 communicating with the bottom of the chemical mixing tank 39. This tank may contain a charge 40 of carbonate extinguishing liquid 55 or other suitable pressure producing chemi-

cal and the starting device may coöperate therewith so as to produce the desired chemical pressure under emergency conditions. This starting device may comprise the primary chemical or acid chamber 84 containing 70 a charge 85 of sulfuric acid or other suitable chemical which tends to flow through the discharge pipe 138 into the mixing tank. This discharge pipe or connection may comprise the trap 136 in which may be located a 75 restraining device such as the mercury seal 42 normally forced up through the transfer pipe 13, the lower end 12 of which dips into the mercury charge 11 in the actuating chamber 10. The actuating pressure pipe 9 may 80 connect with any suitable part of the distributing system so as to transmit the pressure of the air or liquid therein to the tank and force the mercury seal into its restraining position indicated in Fig. 3. Under 85 emergency conditions, however, this pressure on the actuating tank is decreased sufficiently so that the mercury seal is withdrawn from the discharge pipe and the acid charge 85 quickly flows up over the siphon portion 137 90 of the pipe into the mixing tank, the equalizing pipe 41 allowing this flow to take place without interruption.

Any suitable pressure maintaining device 95 may be used in connection with this form of the apparatus so as to supply additional amounts of acid or pressure producing chemical to the tank whenever the gas pressure falls therein and as indicated the chemical may be arranged in a moving or tilting container from which it is discharged by pressure control means, such as the liquid in which this container is more or less floating. The supplemental charge of acid or chemical 100 48 may be arranged within the tilting container 52 pivoted, for instance, about the pivots 46 in the casing 43 connected to the tank through the throat 51. The lower part of this casing 43 is adapted to contain mercury or other sustaining liquid 49 in which 105 the container is more or less floating under emergency conditions and the casing is connected by the governing transfer pipe 50 with the governing pressure chamber 36 so that on decrease of the gas pressure in the 110 tank more mercury flows into the chamber so as to lift and tilt the acid container and discharge part of its contents through the spout 47 into the tank as indicated in Fig. 4. If desired the pressure governing chamber 115 120 36 may be provided with an over-pressure reservoir pipe 38 so as to take care of excess pressures. If desired also part of the mercury charge for the casing 43 may be contained in a weighting compartment 44 on the 125 container so that the parts, under normal inactive condition of the system, are in the position indicated in Fig. 3. When, however, the system comes into emergency operation the increase of gas pressure in the 130

tank drives the mercury up into the pressure governing chamber 36 so that the container tilts downward away from its pivot and a large part at least of the supplemental charge 45 of mercury is discharged from this compartment into the casing 43 so as to increase the amount of mercury therein.

Another arrangement is shown in Fig. 5 as preferably comprising a wet pipe distributing system comprising the supply pipe 3 and the distributing line 6 having any suitable distributing devices or sprinkler heads 7. The check valve 4 may be arranged to maintain the desired non-freezing or other extinguishing liquid in the system under normal conditions and if desired an automatically closing ball check venting device 5 may be arranged below the valve between it and the supply connection 2 extending into the carbonate or other chemical charge 8 in the mixing tank 1. A pin-hole equalizing aperture 60 is preferably arranged in this connection as in the case of the Fig. 1 arrangement. The acid or co-operating pressure generating chemical 129 may be contained in a casing or chamber 127 mounted on the tank and provided with a discharge aperture 131 normally held closed by the control valve 130. This valve 30 may be mounted on the stem 128 secured by the nuts or washers 124 to the flexible metallic or other control diaphragm 125 mounted within the cover 126 of the casing. A spring 123 is arranged above this diaphragm 35 and the adjusting nut 122 may be adjusted above this spring so as to regulate the pressure within the chamber which will tend to keep the diaphragm closed. Under normal inoperative conditions where the tank is under atmospheric or other pressure less than the usual high emergency discharge pressure this diaphragm valve tends to open and a suitable restraining device is used in connection therewith to normally keep it closed 40 until the system comes into emergency operation. A mercury float restraining device may be used for this purpose and may comprise the float 116 of any suitable material arranged within the float chamber 114 and 45 pivoted by the pin 117 to the restraining lever 118. The other end of this lever is pivoted by the pin 120 to the bracket 121 on the casing cover and under normal conditions the lever is held up against the underside 50 of the head 119 on the valve stem by the mercury 115 around the float 116. This mercury is under normal conditions forced up from the actuating chamber 10 by the action of the actuating pressure transfer pipe 9 55 which transmits the liquid or other pressure from the system so that it acts on top of the mercury 11 in this chamber and forces it into the end 12 of the transfer pipe 13 so as to raise it into the float chamber to about 60 the extent indicated. This powerful re-

straining closing action is exerted on the valve stem and valve which is thus kept tightly closed under normal conditions. When, however, one of the distributing devices opens and allows the pressure in the system to fall the mercury is no longer held up in the float chamber and its fall allows the float and connected control or restraining lever 118 to descend so that the control spring 123 quickly opens the valve 130 and 70 allows sufficient acid to run into the tank to quickly develop the desired emergency pressure therein. This pressure is transmitted through the equalizing pipe 141 to the casing below the diaphragm so that as soon as the predetermined emergency discharge pressure is reached the diaphragm is pushed upward against its spring and tightly closes the control valve 130. Any decrease in this amount of pressure above the atmospheric 80 pressure which is acting on the upper side of the diaphragm quickly causes a corresponding supplemental flow of acid so that as long as any of the acid charge remains the tank pressure is kept at substantially 85 the predetermined emergency pressure. Under these emergency conditions also the emergency pressure from the tank and equalizing pipe 141 is transmitted through the pipe 142 to the top of the closed float 90 chamber 114 so that the mercury tends to descend into the actuating tank 10 and remain there so as to have no further action on the float 116.

It is of course desirable to form the acid 100 containers and co-operating trapped portions of the communicating discharge passages with which the mercury and acid co-operate of some suitable material which is not undesirably acted upon by these substances. 105 If desired, glass or chemical earthenware may be used for these parts of the apparatus and also preferably for the co-operating actuating governing chambers, although acid does not have such extended or continued 110 contact therewith. In some instances, however, a suitable protective coating, such as bakelite, or other resistant coating preferably of a somewhat elastic resilient character may as indicated in Fig. 2 be applied to cast 115 iron or other suitable metal chambers and connected pipes having proper form so that the acid and mercury are prevented from having undesirable direct contact with the metal.

This invention has been described in connection with a number of illustrative embodiments, forms, arrangements, materials, proportions, sizes and parts of the apparatus, to the details of which disclosure the invention is not of course to be limited, since what is claimed as new and what is desired to be secured by Letters Patent is set forth in the appended claims:

1. In automatic fire extinguishing appa- 130

ratus, a distributing system comprising distributing devices, a supplemental supply of extinguishing liquid connected to said system and comprising a chemical mixing tank charged with carbonate liquid and coöperating mixing devices including a starting device comprising a starting charge of acid and communicating with said tank, a restraining device cooperating with said starting device, an actuating pressure pipe connecting said restraining device and said distributing system, to effect the discharge of said acid into said tank to generate emergency pressure therein under fire emergency conditions, and means to maintain the emergency pressure in said tank comprising a supplemental acid feeding chamber having a discharge passage communicating with said tank, a governing transfer pipe connected to the lower part of said feeding chamber, a pressure governing chamber connected to said governing transfer pipe and located above said feeding chamber, an over-pressure reservoir pipe connected to said governing transfer pipe and extending above said pressure governing chamber, a charge of mercury normally located in said feeding chamber, a supplemental charge of acid in said feeding chamber in contact with said mercury, said pressure governing chamber being located at a height above said feeding chamber producing a gravity head corresponding with the emergency pressure in said tank to effect the forcing of said mercury into said pressure governing chamber under emergency conditions to feed the acid from said feeding chamber into said tank by the plunger action of the mercury from said pressure governing chamber whenever the tank pressure falls below the normal emergency pressure.

2. In automatic fire extinguishing apparatus, a distributing system comprising distributing devices, a supplemental supply of extinguishing liquid connected to said system and comprising a chemical mixing tank charged with carbonate liquid and coöperating mixing devices including a starting device to effect the discharge of said acid into said tank to generate the emergency pressure therein under fire emergency conditions, and means to maintain the emergency pressure in said tank comprising a supplemental acid feeding chamber having a discharge passage communicating with said tank, a governing transfer pipe connected to the lower part of said feeding chamber, a pressure governing chamber connected to said governing transfer pipe and located above said feeding chamber, an over-pressure reservoir pipe connected to said governing transfer pipe and extending above said pressure governing chamber, a charge of mercury normally located in said feeding chamber, a supplemental charge of acid in said feeding

chamber in contact with said mercury, said pressure governing chamber being located at a height above said feeding chamber producing a gravity head corresponding with the emergency pressure in said tank to effect the forcing of said mercury into said pressure governing chamber under emergency conditions to feed the acid from said feeding chamber, into said tank by the plunger action of the mercury from said pressure governing chamber whenever the tank pressure falls below the normal emergency pressure.

3. In automatic fire extinguishing apparatus, a distributing system comprising distributing devices, a supplemental supply of extinguishing liquid connected to said system and comprising a chemical mixing tank charged with carbonate liquid and coöperating mixing devices including a starting device to effect the discharge of said acid into said tank to generate emergency pressure therein under fire emergency conditions, and means to maintain the emergency pressure in said tank comprising a supplemental acid feeding chamber having a discharge passage communicating with said tank, a governing transfer pipe connected to the lower part of said feeding chamber, a pressure governing chamber connected to said governing transfer pipe and located above said feeding chamber, a charge of mercury normally located in said feeding chamber, a supplemental charge of acid in said feeding chamber in contact with said mercury, said pressure governing chamber being located at a height above said feeding chamber producing a gravity head corresponding with the emergency pressure in said tank to effect the forcing of said mercury into said pressure governing chamber under emergency conditions to feed the acid from said feeding chamber into said tank by the plunger action of the mercury from said pressure governing chamber whenever the tank pressure falls below the normal emergency pressure.

4. In fire extinguishing apparatus, a supplemental supply of extinguishing liquid adapted to be connected to the distributing system and comprising a chemical mixing tank charged with chemical and means to cause an emergency pressure in said tank, and means to maintain the emergency pressure in said tank comprising a supplemental acid holder formed with a depending discharge pipe, a supplemental acid feeding chamber into which said discharge pipe projects, and having a discharge passage communicating with said tank, a governing transfer pipe connected to the lower part of said feeding chamber, a pressure governing chamber connected to said governing transfer pipe and located above said feeding chamber, an over-pressure reservoir pipe connected to said governing transfer pipe

chamber in contact with said mercury, said pressure governing chamber being located at a height above said feeding chamber producing a gravity head corresponding with the emergency pressure in said tank to effect the forcing of said mercury into said pressure governing chamber under emergency conditions to feed the acid from said feeding chamber, into said tank by the plunger action of the mercury from said pressure governing chamber whenever the tank pressure falls below the normal emergency pressure. 70 75

3. In automatic fire extinguishing apparatus, a distributing system comprising distributing devices, a supplemental supply of extinguishing liquid connected to said system and comprising a chemical mixing tank charged with carbonate liquid and coöperating mixing devices including a starting device to effect the discharge of said acid into said tank to generate emergency pressure 85 therein under fire emergency conditions, and means to maintain the emergency pressure in said tank comprising a supplemental acid feeding chamber having a discharge 90 passage communicating with said tank, a governing transfer pipe connected to the lower part of said feeding chamber, a pressure governing chamber connected to said governing transfer pipe and located above 95 said feeding chamber, a charge of mercury normally located in said feeding chamber, a supplemental charge of acid in said feeding chamber in contact with said mercury, said pressure governing chamber being located at a height above said feeding chamber producing a gravity head corresponding with the emergency pressure in said tank to effect the forcing of said mercury into said pressure governing chamber under emergency conditions to feed the acid from said feeding chamber into said tank by the plunger action of the mercury from said pressure governing chamber whenever the tank pressure falls below the normal emergency pressure. 100 105 110

4. In fire extinguishing apparatus, a supplemental supply of extinguishing liquid adapted to be connected to the distributing system and comprising a chemical mixing tank charged with chemical and means to cause an emergency pressure in said tank, and means to maintain the emergency pressure in said tank comprising a supplemental acid holder formed with a depending discharge pipe, a supplemental acid feeding chamber into which said discharge pipe projects, and having a discharge passage communicating with said tank, a governing transfer pipe connected to the lower part of said feeding chamber, a pressure governing chamber connected to said governing transfer pipe and located above said feeding chamber, an over-pressure reservoir pipe connected to said governing transfer pipe 130 115 120 125 130

sure governing chamber, a charge of liquid of greater specific gravity than said chemical charge and normally located in said feeding chamber, said pressure governing chamber being of such size as to be substantially filled when the liquid is first forced thereinto and being located above said feeding chamber to produce a pressure corresponding with the desired pressure in said 10 tank to effect the forcing of said liquid into said pressure governing chamber under the desired pressure conditions and to effect the feeding of chemical into said tank by the plunger action of the liquid from said pressure governing chamber when the tank pressure falls below the desired pressure.

12. In chemical pressure devices adapted for use in automatic fire extinguishing apparatus, a chemical mixing tank charged 20 with pressure producing chemical, means to maintain the pressure in said tank comprising a supplemental chemical feeding chamber containing a coöperating chemical charge having a discharge passage communicating 25 with said tank and coöperating chemical discharging means comprising a governing transfer pipe connected to said feeding chamber, a pressure governing chamber connected to said governing transfer pipe and 30 located above said feeding chamber, an over-pressure device connected to said governing transfer pipe, a charge of liquid of greater specific gravity than said chemical charge and normally located in said feeding chamber, said pressure governing chamber being 35 located above said feeding chamber to produce a pressure corresponding with the desired pressure in said tank to effect the forcing of said liquid into said pressure governing chamber under the desired pressure conditions and to effect the feeding of chemical into said tank by the action of the liquid from said pressure governing chamber when the tank pressure falls below the desired 45 pressure.

13. In chemical pressure devices adapted for use in automatic fire extinguishing apparatus, a chemical mixing tank charged with pressure producing chemical, means to 50 maintain the pressure in said tank comprising a supplemental chemical feeding chamber containing a coöperating chemical charge having a discharge passage communicating with said tank and coöperating chemical discharging means comprising a governing transfer pipe connected to said feeding chamber, a pressure governing chamber connected to said governing transfer pipe and 55 located above said feeding chamber, a charge of liquid of greater specific gravity than said chemical charge and normally located in said feeding chamber, said pressure governing chamber being located above said feeding chamber to produce a pressure corresponding with the desired pressure in said

70 tank to effect the forcing of said liquid into said pressure governing chamber under the desired pressure conditions and to effect the feeding of chemical into said tank by the action of the liquid from said pressure governing chamber when the tank pressure falls below the desired pressure.

14. In automatic fire extinguishing apparatus, a distributing system charged with extinguishing liquid and comprising automatic distributing devices, a supplemental supply of extinguishing liquid connected to said system and comprising a chemical mixing tank charged with carbonate extinguishing liquid and coöperating mixing devices 85 including a starting device comprising a starting chamber having a starting charge of acid chemical therein and having a discharge passage communicating with said tank, a restraining device coöperating with 90 the discharge passage of said starting device and comprising an actuating pressure pipe connecting said restraining device and said distributing system, to prevent discharge of said starting charge into said tank under 95 normal conditions, and to effect the discharge of said starting charge into said tank under fire emergency conditions to generate emergency pressure therein and means to maintain the emergency pressure in said tank.

15. In automatic fire extinguishing apparatus, a distributing system charged with extinguishing liquid and comprising automatic distributing devices, a supplemental 100 supply of extinguishing liquid connected to said system and comprising a chemical mixing tank charged with extinguishing liquid, and coöperating mixing devices including a starting device comprising a starting chamber having a starting charge of chemical therein and having a discharge passage communicating with said tank, a restraining device coöperating with the discharge passage of said starting device and comprising an 110 actuating pressure pipe connecting said restraining device and said distributing system, to prevent discharge of said starting charge into said tank under normal conditions, and to effect the discharge of said 115 starting charge into said tank under fire emergency conditions to generate emergency pressure therein.

16. In fire extinguishing apparatus, a distributing system comprising distributing devices, a supplemental supply of extinguishing liquid connected to said system and comprising a chemical mixing tank charged with extinguishing liquid and coöperating 120 mixing devices including a starting device comprising a starting chamber having a starting charge of chemical therein and having a discharge passage communicating with said tank, a restraining device coöperating with the discharge passage of said starting 125

130

- prising a charge of heavy liquid to form a restraining liquid seal preventing discharge of said starting charge into said tank under normal conditions, said seal being withdrawn from said trap to effect the discharge of said starting charge into said tank to generate emergency pressure therein.
22. In fire extinguishing apparatus, a distributing system comprising distributing devices, a supply of extinguishing liquid connected to said system and comprising a chemical mixing tank charged with extinguishing liquid and coöperating mixing devices including a starting device comprising a starting chamber having a starting charge of chemical therein and having a discharge passage formed with a trap and communicating with said tank, a restraining device connected with said starting device and with said system and comprising an actuating chamber and an actuating transfer pipe connecting said actuating chamber and said trap, and a charge of mercury normally forced into said actuating transfer pipe and trap to form a restraining mercury seal preventing discharge of said starting charge into said tank under normal conditions, said seal being withdrawn from said trap into said actuating chamber under emergency conditions to effect the discharge of said acid into said tank to generate emergency pressure therein.
23. In fire extinguishing apparatus, a distributing system comprising distributing devices, a supply of extinguishing liquid connected to said system and comprising a chemical mixing tank and coöperating mixing devices including a starting device comprising a starting chamber having a starting charge of chemical therein and having a discharge passage formed with a trap and communicating with said tank, and a restraining device connected with said starting device and with said system and comprising a charge of mercury to form a restraining mercury seal preventing discharge of said starting charge into said tank under normal conditions, said seal being withdrawn from said trap to effect the discharge of said starting charge into said tank to generate emergency pressure therein.
24. In automatic fire extinguishing apparatus, a distributing system charged with non-freezing extinguishing liquid and comprising automatic distributing devices including automatic sprinkler heads, a supplemental supply of extinguishing liquid connected to said system through a vented valved connection, and comprising a chemical mixing tank charged with carbonate extinguishing liquid and coöperating mixing devices including a starting device comprising a starting acid chamber having a starting charge of acid therein and having a starting charge of acid therein and having a dis-
- charge passage formed with a trap and communicating with said tank, a restraining device coöperating with said starting device and comprising an actuating chamber below said trap and an actuating transfer pipe connecting said actuating chamber and said trap, an actuating pressure pipe connecting said actuating chamber and the upper part of said distributing system, a charge of mercury normally forced into said actuating transfer pipe and trap to form an acid restraining mercury seal preventing discharge of said starting charge of acid into said tank under normal conditions, said mercury seal being withdrawn from said trap into said actuating chamber under emergency conditions to effect the discharge of said acid into said tank to generate emergency pressure therein.
25. In automatic fire extinguishing apparatus, a distributing system charged with extinguishing liquid and comprising automatic distributing devices, a supplemental supply of extinguishing liquid connected to said system and comprising a chemical mixing tank charged with carbonate extinguishing liquid and coöperating mixing devices including a starting device comprising a starting acid chamber having a starting charge of acid therein and having a discharge passage formed with a trap and communicating with said tank, a restraining device coöperating with said starting device and comprising an actuating chamber below said trap and an actuating transfer pipe connecting said actuating chamber and said trap, an actuating pressure pipe connecting said actuating chamber and the upper part of said distributing system, a charge of mercury normally forced into said actuating transfer pipe and trap to form an acid restraining mercury seal preventing discharge of said starting charge of acid into said tank under normal conditions, said mercury seal being withdrawn from said trap into said actuating chamber under emergency conditions to effect the discharge of said acid into said tank to generate emergency pressure therein.
26. In automatic fire extinguishing apparatus, a distributing system charged with extinguishing liquid and comprising automatic distributing devices, a supplemental supply of extinguishing liquid connected to said system and comprising a chemical mixing tank charged with carbonate extinguishing liquid and coöperating mixing devices including a starting device comprising a starting acid chamber having a starting charge of acid therein and having a discharge passage formed with a trap and communicating with said tank, a restraining device coöperating with said starting device and comprising an actuating chamber below said trap and an actuating transfer pipe connecting said actuating chamber and said trap, an actuating

- pressure pipe connecting said actuating chamber and said distributing system, a charge of mercury normally forced into said actuating transfer pipe and trap to form an acid restraining mercury seal preventing discharge of said starting charge of acid into said tank under normal conditions, said mercury seal being withdrawn from said trap into said actuating chamber under emergency conditions to effect the discharge of said acid into said tank to generate emergency pressure therein.
27. In automatic fire extinguishing apparatus, a distributing system charged with extinguishing liquid and comprising automatic distributing devices, a supplemental supply of extinguishing liquid connected to said system and comprising a chemical mixing tank charged with carbonate extinguishing liquid and coöperating mixing devices including a starting device comprising a starting acid chamber having a starting charge of acid therein, and having a discharge passage formed with a trap and communicating with said tank, a restraining device connected with said system and with said starting device and comprising a charge of mercury normally forced into said actuating transfer pipe and trap to form an acid restraining mercury seal preventing discharge of said starting charge of acid into said tank under normal conditions, said mercury seal being withdrawn from said trap into said actuating chamber under emergency conditions to effect the discharge of said acid into said tank to generate emergency pressure therein.
28. In fire extinguishing apparatus, a distributing system, a supply of extinguishing liquid connected to said system and comprising a chemical mixing tank and coöperating mixing devices including a device comprising a chamber having a charge of pressure producing chemical therein and having a discharge passage formed with a trap and communicating with said tank, and a restraining device connected with said device and with said system and comprising a body of mercury to form a restraining mercury seal preventing discharge of said chemical charge into said tank under normal conditions, said seal being withdrawn from said trap to effect the discharge of said chemical charge into said tank to generate pressure therein.
29. In fire extinguishing apparatus, a distributing system, a supply of extinguishing liquid connected to said system and comprising a chemical mixing tank and coöperating mixing devices including a device comprising a chamber having a charge of pressure producing chemical therein and having a discharge passage formed with a trap and communicating with said tank, and a restraining device connected with said device and with said system and comprising a body of heavy liquid to form a restraining liquid seal preventing discharge of said chemical charge into said tank under normal conditions, said seal being withdrawn from said trap to effect the discharge of said chemical charge into said tank to generate pressure therein.
30. In fire extinguishing apparatus, a distributing system, a supply of extinguishing liquid connected to said system and comprising a chemical mixing tank and coöperating mixing devices including a device comprising a chamber having a charge of acid chemical therein and having a discharge passage formed with a trap and communicating with said tank, and a restraining device connected with said device and with said system and comprising a body of mercury to form a restraining mercury seal preventing discharge of said acid charge into said tank under normal conditions, said seal being withdrawn from said trap to effect the discharge of said acid charge into said tank to generate pressure therein.
31. In fire extinguishing apparatus, a distributing system, a supply of extinguishing liquid connected to said system and comprising a chemical mixing tank and coöperating mixing devices including a device comprising a chamber having a charge of pressure producing chemical therein and having a discharge passage formed with a trap and communicating with said tank, and a restraining device connected with said device and with said system and comprising a body of heavy liquid to form a restraining liquid seal preventing discharge of said chemical charge into said tank under normal conditions and means controlled by said system to withdraw said seal from said trap to effect the discharge of said chemical charge into said tank to generate pressure therein.
32. In fire extinguishing apparatus, a distributing system, a supply of extinguishing liquid connected to said system and comprising a chemical mixing tank and coöperating mixing devices including a device comprising a chamber having a charge of acid chemical therein and having a discharge passage formed with a trap and communicating with said tank, and a restraining device connected with said device and with said system and comprising a body of mercury to form a restraining mercury seal preventing discharge of said charge into said tank under normal conditions, and means controlled by the pressure conditions of said distributing system to withdraw said seal from said trap to effect the discharge of said acid charge into said tank to generate pressure therein.
33. In chemical fire extinguishing apparatus, a chemical mixing tank charged with pressure producing chemical, means to cause and maintain the operating pressure in said
